CLAIM

The ornamental design for a bowfishing reel line deflector, substantially as shown and described.

DESCRIPTION

FIG. 1 is a front, left side perspective view of a bowfishing reel according to the present invention;

FIG. 2 is a left side elevation view of the bowfishing reel of FIG. 1;

FIG. 3 is a right side elevation view of the bowfishing reel of FIG. 1;

FIG. 4 is a front elevation view of the bowfishing reel of FIG. 1;

FIG. 5 is a rear elevation view of the bowfishing reel of FIG. 1;

FIG. 6 is a top plan view of the bowfishing reel of FIG. 1; and,

FIG. 7 is a bottom plan view of the bowfishing reel of FIG. 1.

The broken lines are for illustrative purposes and represent environmental structure and unclaimed portions of the invention and therefore form no part of the claimed design.
